Primary Examiner—Stacia Cadmus

(74) *Attorney, Agent, or Firm*—Thomas R. Kingsbury

(57) **CLAIM**

The ornamental design for a tire sidewall, as shown and described.

DESCRIPTION

FIG. 1 is a side elevation view of the tire sidewall showing my new design; and,

FIG. 2 is an enlarged side elevation view of a segment of the sidewall of FIG. 1.

The broken lines defining the tire are for illustrative purposes only and form no part of the claimed design.

1 Claim, 2 Drawing Sheets

FIG-1

FIG-2
